LEE B. KUHN, OF BROOKLYN, NEW YORK

MATCH PACKAGE

Application filed May 14, 1930. Serial No. 452,272.

This invention relates to packages of matches such as are commonly known as book matches. Among the objects of the invention is to provide improvements which render such packages more convenient in use and at the same time to provide a construction which lends itself in a unique way to advertising purposes, thereby achieving two distinct advantageous results in a single novel construction.

In carrying out the invention, all of the usual features of construction of such packages which have heretofore been commonly employed may be retained, in combination with the new features introduced by the present invention. An improvement in accordance with this invention comprises a freely projecting front terminal flap or tab which when pulled draws the front cover for the matches out into substantially straight alignment with this tab. This tab is on upwardly projecting front terminal section forming an extension in one-piece with the front cover section to which it is joined along a reverse fold line, this flap section being thus reversely folded outwardly and upwardly at the front of the front cover. In the closed condition of the package, the double thickness, formed by the superposed folded edge portions of the front cover section and the tab-forming front terminal section, is inserted behind and retained in the closed and folded position by the usual free upwardly projecting lower lip.

In the open condition of the package, the normally inner side of the front cover section will be exposed substantially in alignment with the front face of the tab-forming front flap, since the reverse fold will now be straightened out. Accordingly, a pictorial representation of an object to be advertised may be represented as to its upper portion on the front face of the free flap or tab while the lower portion of the same object will appear in unbroken downward continuation on the inner side of the front cover, so that thereby with the package open, the entire picture of the object is presented to view, while with the package closed only the upper portion of this picture can be seen. Further-

more, this freely projecting front flap which forms the tab may be cut to the outline of the upper portion of the object which is represented thereon.

Also, in further carrying out the invention, other flaps may be joined along fold lines to the sides of the front cover section, normally being in an inwardly folded concealed condition and to be unfolded outward to a flat condition after the front tab has been pulled out. The invention will be further described with reference to the accompanying drawings, illustrating a few slightly variant embodiments of the invention, and in which:

Fig. 1 is a perspective view of one embodiment of the invention with the package in its closed condition;

Fig. 2 is a front face view of the same package in its fully open condition;

Fig. 3 is a side edge elevation of the closed package shown in Fig. 1;

Fig. 4 is a front face view of a closed package embodying a slightly variant form of the invention including a further feature;

Fig. 5 is a front face view of this latter package in its fully open condition;

Fig. 6 is a similar view of a form of the invention further embodying an additional flap, the folded position of which is indicated by broken lines;

Fig. 7 is a front face view in partly unfolded condition of another form of the invention having two additional flaps shown in their folded condition; and

Fig. 8 is a partial front face view of this latter package in its fully open condition.

A relatively simple form of the invention is shown in Figs. 1, 2 and 3. Paper match sticks 1 having individual ignition heads 2 are joined together at their other ends by means of a straight base strip 3, to form a usual match card in which the match sticks 1 may be torn from the base strip 3. Two of such match cards are shown in the package, this being the usual number. A one-piece cardboard enclosing cover or casing, including substantially the usual features, is provided for the match cards and secured thereto in a usual way. This casing is commonly formed from a single strip of material, made

up of folded sections, which as to some of them may be more or less straightened out, and in carrying out this invention, a single continuous strip of material is still employed, but of somewhat greater length and comprising an additional fold therein in the closed condition of the package, but which is straightened out when the package is opened, this additional fold being a reverse fold.

10 The match-enclosing cover casing shown comprises a flat back member section 4 and a lower front terminal section 5 formed as an extension of the lower portion of the back section 4, folded forwardly and upwardly 15 around and over the lower edges of the match-carrying base strips 3. Suitable fastening means are shown in the drawings as a usual single wire staple 6 which passes through and connects together the lower portion of the 20 lower front terminal section 5, the base strips 3 adjacent their lower edges, and the lower marginal portion of the back section 4. The lower front section 5 projects freely upwardly from this securing staple 6 in the form of a 25 free or unattached lip at the front of the front match-carrying base strip 3. A usual striking surface 7 is shown as provided on the front face of this lower front terminal section 5. The material of the strip forming 30 the back section or member 4 is continued through a more or less curved bent intermediate end connecting portion 8, over or around the ignition heads 2 and downward at the front of the matches 1, as a front cover member or section 9, thus far substantially as 35 usual.

This front cover 9, however, does not form a terminal section of the cover strip of the casing, as is commonly the case. In accordance with the invention, this strip of material 40 forming the match cover or casing as so far described, is continued through a short or sharp reverse fold line 10 into a free front flap 11 which projects reversely or upward at the 45 outside of the front face of the front cover 9, having no connection with the latter excepting through the reverse fold 10 by which it is joined thereto to form an extension thereof.

50 In the closed conditions of the package, as shown in Figs. 1 and 3, the double thickness lower margin formed by the superposed lower portions of the front cover section 9 and the projecting tab section 11, which come together in the reverse fold 10, is inserted behind or beneath the free upwardly projecting front lip provided by the lower front terminal section 5, the free edge of which has a natural tendency to stand slightly away from or in spaced relation to the underlying base strip 3 of the adjacent match card. The rounded edge formed by the reverse fold 10 also facilitates the insertion. The upwardly projecting free edge portion of the front tab flap 11 55 has a natural tendency to spring somewhat

away from the front face of the front cover section 9, as indicated in Figs. 1 and 3, which facilitates its being grasped between the tips of the forefinger and thumb.

When the free tab-forming terminal front flap 11 is pulled upward, it will withdraw the fold 10 from beneath the lip of the lower front terminal section 5, and this pull upon the tab 11 will straighten out the reverse fold 10 as the front cover section 9 is brought substantially into alignment with this front flap section 11, and also into substantial alignment with the back section 4, in the fully opened condition of the package shown in Fig. 2. The projecting front flap or tab 11 70 may be of greater or less length, as may be desired or as deemed advisable in any particular instance. It is desirable, however, that this releasing tab 11 should only partially cover the front face of the match-covering front section 9, so as thereby to be more conveniently grasped, as well as also for presenting advertising to better advantage. 75

80 Thus an advertisement starting at the top of the front face of the front cover section 9 will have its upper portion exposed to view in the closed condition of the package and may be continued in sequence down behind the tab flap 11. Or if desired, an introductory portion of an advertisement may begin 85 at the top of the front cover section 9 and have a sequence continuation down over the front face of the tab flap 11. Furthermore, an advertisement beginning on or continued 90 upon the front face of the tab 11 may be continued in sequence without break upon the inner face of the front cover section 9, so that thereby this lower portion of the advertisement will be brought to view as a continuation of its upper portion when the cover 95 section 9 is straightened out to the reverse position thereof in the opened condition of the package shown in Fig. 2. 100

105 Advertising matter such as above noted is indicated in Figs. 1 and 2. Obviously, this advertising matter may include pictures. For example, one complete picture may appear on the exposed front face of the tab section 11 and another complete picture, having a related sequence with the first, may appear upon the inner face of the front cover 9, thereby to be brought into view in connection with the first picture in the open condition of the package, as in Fig. 2. Or the upper portion only of a single picture, such as 110 of a person or of a commodity, may appear on the front face of the tab 11 and the picture be continued unbroken across the fold line 10 and along the inner face of the front cover 9, so that thus the complete connected 115 picture will be presented to view only in the opened condition of the package. 120

125 In further carrying out the invention, the projecting package-opening tab or front extension flap may desirably be cut to the shape 130

or to form the outline or silhouette of any object or picture thereof, and in such case this flap or tab may desirably be of somewhat less width than the full width of the front cover section 9 for the matches. One example of such a variation or further development in carrying out of the invention is illustrated in Figs. 4 and 5. In that instance, a pull-out tab 12 is shown which is of less width than the front match cover section 9, with the end of which it forms lateral shoulders at 13. With the exception of this variation or modification in construction the rest of the match package there shown may be and is shown as of the same construction as above described with reference to Figs. 1, 2 and 3, and accordingly the same reference numerals have been applied throughout in Figs. 4 and 5.

This tab 12 is shown as cut to the outline of the shape of one end portion of a commodity which is advertised and also has on its front face a representation or picture of the upper portion of this commodity, such picture being continued without break beyond the fold line 10 downwardly over the inner face of the front match cover section 9, as shown in Fig. 5. In the illustrated example, a perspective view is shown of a usual form of container or pasteboard outer casing, which is shown as being open at its lower end to display the cap end of a usual collapsible tube which contains the commodity which is thus advertised in picture form, together with a printed label on the outside of the outer casing, all as indicated in the drawings.

It will be noted that the pictorial representation of the closed end portion of this outer casing appears on the front face of the tab flap 12, which is cut to the perspective outline of the upper end portion of the picture, while the picture is continued without a break therein over the inner face of the match-covering front section 9, in larger flaring dimensions, according to the perspective view of the commodity there shown, the lower end portion of this picture being shown as of substantially the full width of this cover section 9. In this instance the perspective taper of the picture determines the shape of the opening tab 12, which accordingly forms the shoulders 13, beyond which it tapers outwardly and upwardly, terminating in an angle at the end of this tab 12. This shape or outline of the tab 12 renders it even more convenient to be grasped for straightening out the joined sections than in the case of an uncut or unshaped tab, such as shown in Figs. 1, 2 and 3.

It should be obvious that a shaped or cut-out tab such as 12 may take the outline of any object desired. For example, an upright or standing picture of a person, such as a bathing beauty, may appear in part on the releas-

ing tab, such as 12, and in part on the inner face of the front match cover 9, with this tab cut to the outline of the upper portion of the picture, which will appear complete in the open condition of the package, as shown in Fig. 5, and which may be accompanied by suitable advertising text with reference to bathing facilities at some designated place. The upper portion of such a picture on the releasing tab may extend, for example, down to about or a little below the waist line of the standing bather.

Similarly, as another variant example, a head or a bust representation of a person may appear in both picture and outline on the releasing tab, such for example as of an author, public speaker, or actor, to be followed by advertising matter below such picture on the inner side of the front cover section 9. In fact, there is practically no limit to what may be advertised in this way, in the form of an outlined picture, and the invention has been actually practically carried out with numerous such examples. Thus it is seen that the invention may be said to have a dual utility, or to combine two useful results in its construction, one of which is for advertising purposes in a particularly advantageous way, and the other of which is the increased convenience in opening and closing the package of matches.

Obviously different securing means, other than the staple 6, could be employed, such as a series of similar staples, which could then be smaller; or the securing means could be a line of stitching. It is essential that the securing means, such as the wire staple 6, shall hold in place the lower front terminal section 5, in order that the latter may thereby provide the free projecting cover-holding lip, however, so far as this invention is concerned, it is substantially immaterial whether or not this staple, or other fastening device, passes also through the back section 4, as shown and which is the usual construction in this respect.

The further development of the invention shown in Fig. 6 is in other respects similar to what is shown in Figs. 4 and 5. In this form of the invention a side flap section 14 is joined to the front cover section 9, at the left thereof, along a fold line 15, and normally or in the folded condition of the package lies in an inwardly folded position flat against the inner side of the front cover section, as is indicated in broken lines for the intermediate condition of the package after the front cover section 9 has been drawn out by means of the free tab section 12. The side flap will then spring out a little distance along its free edge from the cover section 9 and may be readily unfolded laterally into flat alignment therewith, as shown in full lines.

As is shown in Fig. 6, this brings into view

the entire object or representation thereof, which begins at the top with the pull-out tab 12, is continued downward in sequence on the front cover section 9, and laterally to the left in further sequence on the side flap section 14. Natural curiosity, of course, will impel a person to follow up the sequence and unfold the side flap 14. The pull-out tab 12 is shown as cut to the silhouette outline of a picture beginning thereon. The representation shown as an example is that of an attractive young woman pleased with the contents of an open container which she holds in her hands. There may be suitable advertising matter adjacent on the side flap 14, as indicated, as well as elsewhere, of course. The side flap 14 of course could be at the other or right side edge of the package, or there could be two such flaps, one at each side. In its folded condition the package shown in Fig. 6 will have substantially the appearance of that shown in Fig. 4.

In further carrying out the invention as shown in Figs. 7 and 8, a side flap section 16 is joined to the front cover section 9, at the right thereof, along a fold line 17, and is normally folded inwardly at the inner side of the front cover 9. A top flap section 18, joined to the side flap 16 along a fold line 19, is normally folded down between the side flap 16 and the inner side of the front cover section 9, as indicated in dotted lines in Fig. 7. Fig. 7 shows the package after the front cover section 9 has been pulled out by means of the free tab section 12, as hereinbefore described. The side flap section 16 then springs slightly forward, as indicated by the position of its edge at the left. When this side flap 16 has been unfolded towards the right, then the second or supplemental top flap section 18 may be unfolded therefrom upwardly into flat alignment therewith. In the fully unfolded condition of the casing, shown in Fig. 8, the front cover section 9, its pull-out tab 12, the side flap 16 and its top flap section 18 are all in flat alignment. Natural curiosity will prompt the successive unfolding of the side flap 16 and top flap 19.

The pull-out tab 12 is cut to the outline of a picture thereon, and the top flap is shown as similarly cut to the outline of a similar picture on the latter. These representations may be accompanied by suitable advertising matter below them, on the inner sides of the front cover section 9 and the side flap 16, as indicated in Fig. 8. Also the other or reverse side of the side flap 16 may be utilized for advertising purposes, as indicated in Fig. 7, as well as other available space. In folding the package, the top flap 18 will first be folded down forwardly, and then the side flap 16 turned over forwardly towards the left, together with the top flap 18 carried thereby, as shown in Fig. 7, in which the top flap 18 is indicated in dotted outline. In its

folded condition the package shown in Figs. 7 and 8 will present substantially the appearance of that shown in Fig. 4.

It is obvious that various modifications may be made in the constructions shown in the drawings and above particularly described, within the principle and scope of the invention as defined in the appended claims.

I claim:

1. A match package of the kind having a card of matches and a cardboard casing therefor secured to the base of such card, in which the said casing comprises a front lip having a free edge portion projecting from the base of the card towards the heads of the matches, a back member for the matches projecting from the base of the said card to a point adjacent the ends of the heads of the matches, and a front cover member for the matches forming an extension of the said back member folded forwardly over the heads of the matches and down at the front to the base of the card where it is received behind the said lip, in combination with an outwardly exposed free front flap constituting a reversely bent upward extension of the front cover member to extend from behind the said lip beyond which it projects upwardly and outwardly so as to form a tab by which the front cover member may be pulled out from beneath the lip and towards a position of alignment with this tab-forming flap in opening the package.

2. In a package of matches comprising one or more cards of matches joined together at the base of such card, a one-piece cardboard casing including a back section, a front cover section forming a free forward and downward continuation from the back section, a lower front terminal section forming a forwardly bent upwardly directed continuation of the back section at the front of the base of the match cards, and securing means passing through the lower edge portions of the match card bases and through the said lower front section of the cover so that thereby the edge portion of the latter forms an upwardly projecting free lip, in combination with a terminal front flap section folded reversely outwardly and upwardly as a reversely bent continuation of the front cover section to project freely upwardly and outwardly at the front of the front cover section from behind the said lip in the closed condition of the package so that thereby when the package is to be opened the said front cover section together with the said front flap may be drawn out from behind the lip and the front cover section at the same time drawn back by means of the said free flap section.

In witness whereof, I hereunto subscribe my signature.

LEE B. KUHN.
